(57) **CLAIM**

The ornamental design for a sound loudspeaker, as shown and described.

DESCRIPTION

FIG. 1 is a perspective view of a sound loudspeaker showing the new design;

FIG. 2 is another perspective view thereof;

FIG. 3 is a front elevation view thereof;

FIG. 4 is a back elevation view thereof;

FIG. 5 is a left-side view thereof;

FIG. 6 is a right-side view thereof;

FIG. 7 is a top plan view thereof;

FIG. 8 is a bottom plan view thereof;

FIG. 9 is an enlarged view of the encircled portion in FIG. 1; and,

FIG. 10 is an enlarged view of the encircled portion in FIG. 2.

The dash-dot-dash lines in FIGS. 1, 2, 9, and 10 illustrate the enlarged view indicators and form no part of the claimed design. The remaining broken lines depict portions of the sound loudspeaker that form no part of the claimed design.
